UNITED STATES PATENT OFFICE

2,036,103

PHONOGRAPH APPARATUS

Paul H. Smythe, Jr., Chicago, Ill.

Application March 14, 1935, Serial No. 11,091

2 Claims. (Cl. 274—10)

This invention relates to phonograph apparatus.

It is an object of this invention to provide an improved phonograph apparatus which is relatively simple and inexpensive in construction and efficient in use.

Another object of the present invention is to provide a novel and improved selector carriage for an automatic phonograph.

10 A further object of the present invention is to provide an improved selector carriage including a relatively stationary guide, a vertically movable element mounted on said guide for movement relative thereto, means for latching the vertically movable element of the selector in raised position relative to the guide, and a novel and improved device for taking up the shock of the vertically movable element, and for causing the same to drop slowly and noiselessly when the said latching means is released from latching engagement relative to the said movable element of the selector.

15 An additional object of the invention is to provide, in combination, a phonograph apparatus including a selector carriage having a relatively stationary guide and a member guided by and vertically movable relative to said guide, means for latching the said movable element in raised position relative to the said guide; and a dash 20 pot for absorbing the shock of the vertically movable element of the selector carriage when the latter is released from latching engagement with the said guide and drops by gravity into its lowered position.

25 Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a side elevational view showing the new apparatus;

Fig. 2 is an edge elevational view of the same, partly in section, and taken on line 2—2 in Fig. 1;

Fig. 3 is a sectional view of the dash pot, taken on line 3—3 in Fig. 2;

Fig. 4 is a transverse sectional view of the dash pot on line 4—4 in Fig. 3; and

50 Fig. 5 is a sectional view on line 5—5 in Fig. 1. The present invention is concerned with the record-selecting device on an automatic phonograph, and as much of said carriage as is necessary for an understanding of the present invention is shown in the drawing, is therein general-

ly indicated at 10, and comprises a guide 11 upon which a member 12 is slidably mounted for vertical movement relative to the guide 11. This 5 slide element 12 of the selector carriage is guided for vertical movement upon, and relative to, the stationary guide member 11 of the selector, as shown in Fig. 5.

The movable element 12 of the selector has a serrated edge 14 and latchingly engageable with this edge 14 is a latch dog 15 which is pivotally mounted upon the relatively stationary guide member 11, the latch dog 15 serving to hold the movable element 12 in raised position relative to the guide member 11.

The movable element 12 of the selector is provided with a lateral extension or arm 16 and carried by, and depending from, this extension 16 is a rod or plunger 17. Attached to the rod or plunger 17, at the lower end of the latter, is a piston 18 which works in a cylinder 19, the piston 20 18 having an air-tight sealing engagement with the inner wall of the cylinder 19 and the cylinder 19 being provided with an air vent 20 adjacent its lower end (Fig. 3).

The cylinder 19 may be supported in any suitable manner, as by means of a bracket 22 attached to the guide 11 of the selector at the lower end of the same.

The piston rod 17, piston 18, and the cylinder 19 provide, in effect, a dash pot, and the device 30 operates as follows:

When the movable element 12 of the selector is raised, (by means not shown), during the record-selecting operation, the said movable element is held in raised position, by the latching 35 engagement of the latch dog 15 with the serrated edge 14, until such time as the latch dog 15 is moved out of latching engagement with the serrated edge 14 (by means not shown).

When the latch dog 15 is moved out of latching engagement with the serrated edge 14 of the movable element 12 of the selector, the movable element 12 falls or drops by gravity, relative to the guide 11, and during this movement of the movable element 12 the rod 17 carried by the 45 movable element 12 drops therewith, thereby forcing the piston 18 downwardly in the cylinder 19 and against the pressure of the air disposed in the area 21 of the cylinder 19 below the piston 18. This movement of the piston 18 compresses 50 the air in the area 21 of the cylinder 19 and forces the same out through the vent opening 20, thereby cushioning the fall of the movable element 12 of the selector carriage and causing the same to fall gradually whereas otherwise the said mov- 55

able element of the selector carriage would drop rapidly, causing noise and damage to the apparatus.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters 15 Patent is:

1. In a phonograph apparatus, a record selector carriage including an elongated upright or vertically extending bar providing a guide and a member slidably mounted upon the said guide 20 for vertical movement relative thereto; means for latching the said movable element in raised position relative to the said guide including a latch dog pivotally mounted upon said guide between

the upper and lower end of the latter; a cylinder; a member carried by said movable element having a piston attached thereto and movable in said cylinder for cushioning the fall or drop of the said movable element, relative to the said guide, when the said movable element is released from latching engagement with the said guide; and means for supporting said cylinder from said guide. 5

2. In a phonograph apparatus, a record selector carriage including an elongated upright or vertically extending bar providing a guide and a member slidably mounted upon the said guide for vertical movement relative thereto; means for latching the said movable element in raised position relative to the said guide including a latch dog pivotally mounted upon the said guide between the upper and lower ends of the latter; a cylinder; a member carried by said movable element having a piston attached thereto and movable in said cylinder; and means for supporting said cylinder from said guide. 15 20
